UNITED STATES PATENT OFFICE

LEONARD I. LAMB, OF ATTLEBORO, MASSACHUSETTS, ASSIGNOR TO R. F. SIMMONS COMPANY, OF ATTLEBORO, MASSACHUSETTS, A COPARTNERSHIP CONSISTING OF JOSEPH L. SWEET AND HAROLD E. SWEET

EXPANSIBLE BRACELET

Application filed July 18, 1928. Serial No. 293,540.

This invention relates to expandible bracelets such for example as are commonly used for supporting wrist watches or the like, and more particularly to an expandible unit which is adapted to be connected to the ends of a wrist-encircling portion of the bracelet to permit the latter readily to be applied to or removed from the wrist.

The present invention provides a compact 10 expandible unit of this character which may be comparatively flat, thus avoiding objectionable projection beyond the surface of the wrist and conforming with modern style trends and usage. The present invention is 15 particularly designed to provide a unit of this character permitting an unusually high degree of expansibility by providing an overlapping arrangement of the resilient elements which are stretched to permit the bracelet to 20 be removed or applied to the wrist, the resilient means preferably being arranged to have substantially parallel portions engaging the ends of the wrist-encircling elements so that the springs may have a comparatively small 25 diameter and thus permit the provision of a more compact unit. The invention is particularly applicable to bracelets of the type which are provided with a single unit of this character, which unit is preferably suitably 30 decorated or embossed to resemble a fancy buckle or the like.

In the accompanying drawings:

Fig. 1 is a top plan view, with a part of the casing broken away, showing the improved 35 expandible connector secured to the wrist-encircling elements;

Fig. 2 is a section on line 2—2 of Fig. 1; and

Fig. 3 is a view similar to Fig. 2, but showing the parts in the positions they occupy 40 when the resilient elements are expanded.

In accordance with the present invention any suitable wrist-encircling means or elements 1, such for example as strips of meshed chain fabric, may have their ends connected 45 by the expandible means designated in general by numeral 2. While obviously the elements 1 may be connected to a wrist watch or similar article, the invention is also applicable to a single wrist-encircling element which has 50 its ends secured to the expandible means 2.

The latter is provided with a central supporting element or plate which preferably may be curved as shown in Fig. 2 to conform to the general shape of the human wrist. The plate 3 carries outstanding lugs 4 which project from opposite faces of the plate at opposite ends thereof. These lugs preferably have curved grooves 5 in each of which the intermediate portion of a coil spring 6 is received. The end portions of these springs 55 terminate in wire convolutions 9 which engage the ends of transverse pins 10 that are received in suitable sheet metal elements 11 carried by the ends of the wrist-encircling elements. This arrangement of the springs 6 provides two spring elements acting in parallel to resist the outward movement of each end of the wrist-encircling portion, thus permitting the provision of a thin compact unit. 60

As shown in Fig. 2, when the springs 6 are in their contracted positions, the ends of the wrist-encircling elements may be substantially above each other, adjoining the middle of plate 3 and being separated by the same. The lugs 4 and the springs 6 are arranged, however, so that when the latter are stretched or expanded they will permit the ends of the corresponding wrist-encircling element to be juxtaposed to the ends of plate 3. This position of parts is illustrated, for 65 example, in Fig. 3, it being evident that the overlapping arrangement of the expanded springs in this manner permits an unusually high degree of expansibility with a single compact expandible means. 70

A suitable decorated covering factor 20 of sheet metal may be arranged about the expandible means 2. This may comprise interfitting casings 21 and 22 which are curved to conform to the shape of the wrist and which are snapped or pressed into engagement with each other. Each of these casings has a closed end 23 adjoining a lug 4 and an open end 24 permitting the wrist-encircling elements freely to move therethrough. Preferably the open ends 24 are provided with flange portions 25 that are adapted to engage the elements 11 to provide stops to limit the expansion of these springs. 75

It is evident that this invention provides a 80

bracelet which may have a single expandible means that may be assembled in a comparatively flat and compact decorative casing, while the overlapping arrangement of the resilient elements permits an unusually high degree of expansibility.

I claim:

1. A bracelet comprising a wrist-encircling portion, expandible means connecting the ends of that portion, an intermediate plate associated with said means, springs at either side of said plate, the ends of the wrist-encircling portion being arranged at opposite sides of the plate and connected to the springs, whereby the springs and ends of the wrist-encircling portion are in overlapping relation to each other.
2. A bracelet comprising a wrist-encircling portion, expandible means connecting the ends of that portion, said ends and means being flat, a casing arranged about the same, said means including a plurality of spring elements connected to each end of the encircling portion within the casing, each end of the encircling element and the spring elements secured thereto being arranged in a plane parallel to that of the other end and the spring elements connected to the same.
3. A bracelet comprising a wrist-encircling portion, expandible means connecting the ends of that portion, said means including a pair of springs arranged at opposite sides of an intermediate plate, lugs at the opposite ends of the plate, an intermediate part of each spring being received in a curved groove upon one of said lugs, the ends of the springs being connected to the encircling portion, whereby the springs when expanded may be in overlapping relation to each other.
4. A bracelet comprising a wrist-encircling portion, and an expandible unit connecting opposite ends of the bracelet, said unit including a longitudinal plate disposed between the bracelet ends, said ends being slidable over the opposite sides of said plate and being normally held in parallel, overlapping relation, and springs connected to the respective ends of the bracelet and to said plate at opposite sides thereof, the springs being arranged substantially in line with the respective bracelet ends so that when the bracelet ends are drawn apart, the extended springs overlap in spaced parallel relation.
5. An expandible connector for opposed ends of a bracelet, comprising a casing having parallel top and bottom portions and a longitudinal plate fixed substantially midway between the top and bottom, providing parallel compartments, each compartment having an open end receiving the respective ends of the bracelet, said open ends being arranged at opposite ends of the connector, studs fixed upon opposite sides of said plate and adjacent opposite ends of the connector, there being a stud in each compartment, and

looped springs extending around the respective studs and attached to the corresponding bracelet ends, said springs normally holding the bracelet ends in overlapping relation, and stretching substantially the length of the compartment when extended by pulling the bracelet ends apart.

Signed by me at Attleboro, Massachusetts, this sixteenth day of July, 1928.

LEONARD I. LAMB.
